(57) **CLAIM**

The ornamental design for stilt and box shelving unit, as shown and described.

DESCRIPTION

FIG. 1 is a perspective view of my new design;
FIG. 2 is a front elevational view thereof;
FIG. 3 is a rear elevational view thereof;
FIG. 4 is a top view thereof;
FIG. 5 is a bottom view thereof; and,
FIG. 6 is a right side view thereof, the left side being a mirror image.
The broken lines shown in FIG. 6 are for illustrative purposes only and form no part of the claimed design.
